UNITED STATES PATENT OFFICE

DONALD K. SLOTEMAN, OF AKRON, OHIO, ASSIGNOR TO THE GOODYEAR TIRE & RUBBER COMPANY, OF AKRON, OHIO, A CORPORATION OF OHIO

DESIGN FOR A TIRE

Application filed July 22, 1931. Serial No. 40,620. Term of patent 3½ years.

To all whom it may concern:

Be it known that I, DONALD K. SLOTEMAN, a citizen of the United States, residing at Akron, in the county of Summit and State of Ohio, have invented a new, original, and ornamental Design for a Tire, of which the following is a specification, reference being had to the accompanying drawings, forming part thereof.

Fig. 1 is a fragmentary plan view of a tire embodying the inventive design; and

Fig. 2 is a cross-sectional view taken on line II—II of Fig. 1.

I claim:

The ornamental design for a tire, as shown.
DONALD K. SLOTEMAN.
